LENS EXTENSION MOUNT FOR PHOTOGRAPHIC RECORDING APPARATUS

David G. Fladlien and David J. Fladlien, Los Angeles, Calif., assignors to Thompson Ramo Wooldridge Inc., Redondo Beach, Calif., a corporation of Ohio

Filed Dec. 30, 1963, Ser. No. 77,974

Term of patent 14 years

(Cl. D61—1)

Fig. 1.

Fig. 2.

Fig. 3.

Fig. 4.

FIGURE 1 is a front perspective view of a lens extension mount for photographic recording apparatus showing our new design;

FIGURE 2 is a top plan view thereof;

FIGURE 3 is a side elevation view thereof; and

FIGURE 4 is a rear perspective view thereof with a portion broken away for convenience of illustration.

We claim:

The ornamental design for a lens extension mount for photographic recording apparatus, substantially as shown.
